SPRING

Robert C. Winders, Walnut Park, Calif.

Application September 26, 1933, Serial No. 691,005

4 Claims. (Cl. 5—272)

This invention relates to springs suitable for use as upholstery. It appertains to a group of coiled spring units tied together to form an assembly. It is desirable that such assemblies be 5 light in weight, the spring units be grouped close together and that a minimum of the covering enveloping the springs be unsupported. Furthermore, the individual spring units should be securely fastened together against separation and 10 slippage with respect to one another, and the whole assembly be capable of being rolled. Due to the weaving of the springs, the ties must allow bending movement of the springs to accommodate themselves to differences in distortion. 15 Unless tying, enabling such movement is effected, the assembly does not have softness. If the springs are tied to allow themselves to slip on one another and to be moved independently of one another, noise may result in use of the 20 springs. My invention contemplates the use of a noise dampening tie.

My invention is illustrated in the accompanying drawing, in which:—

Fig. 1 is a plan view showing a fragment of 25 a spring, a portion of one row being shown; Fig. 2 is a sectional view as seen on the line 2—2 of Fig. 1; and Fig. 3 is a detail sectional view as seen on the line 3—3 of Fig. 2.

Referring more particularly to the drawing, 30 the spring comprises a plurality of coiled spring units 5, the top and bottom convolutions being enlarged in diameter, adjacent tops of the coils in a row are fastened together and likewise adjacent bottoms. The coil units are in general of 35 common type of construction used for coiled springs in upholstery. The spring units 5 being arranged in rows and rows of spring units being assembled parallel to one another with a suitable distance between rows. The spring units 40 in a row are contiguous to one another with the top convolutions and the bottom convolutions locked together by means later described. At contiguous portions of the terminal coils, the latter are bent to provide offset loops 6a and 6b 45 directed axially of the coil units. Loops 6a are of less width than the loops 6b so that when placed side by side in registration a wire 7 may be passed outside of the legs of a loop 6a and inside the legs of its companion loop 6b. It will 50 also be noted that loops 6a are of greater height than loops 6b.

Extending transversely across the rows are tie wires 7 having locks for adjacent springs provided by forming offset loop 8 in the wires. These 55 loops comprise crowns 8a and legs 8b. The

legs 8b are spaced at widths apart such as to lie in the spaces between the legs of loops 6a and 6b with the crowns 8a lying against the inner sides of loops 6a. The crowns of loops 6a form eyes with the crowns of loop 6b whereby cords 9 may be strung therethrough locking the spring units together. The legs of the several loops being interlaced prevent revoluble slipping and hold the units against lateral displacement, yet accommodate the units to flexing. The cords 9 are preferably formed of suitable pliant material such as fibre. The units may be assembled in a spring by disposing them side by side with the loops 6a adjacent loops 6b. The tie wires 7 are laid within loops 6b with the loops 8 directed laterally. Loops 6a are then rove through loops 8 on the outside of loops 6b. Eyes to receive cords 9 are thus provided and cords 9 are threaded therethrough. The cords form a noise dampening lock. The entire assemblage is flexible permitting rolling of the spring. The cords 9 and the wires 7 may be attached at their ends in any desired manner to end coils of the spring of such frame work as may be employed in the completed assembly.

What I claim is:—

1. A spring comprising a plurality of coiled spring units arranged in a row, contiguous spring units in a row having their terminal coils formed with diametrically opposite loops offset axially inward with relation to the units, one loop of a coil being of greater width and less height than its other loop, said coils being disposed with a loop of greater width and a loop of lesser width adjacent one another to form companions, tie wires having offset loops woven through the companion loops of said units, the legs of a tie wire loop extending between the inside of legs of a coil loop of greater width and the outside of legs of its companion coil loop of lesser width, keeper ties of cord extending lengthwise of said row and rove through the eyes formed by the crowns of companion loops.

2. A spring comprising a plurality of coiled spring units arranged in a row, contiguous spring units in a row having their terminal coils formed with loops offset axially with relation to the units, loops of adjacent coils being placed side by side to form companions, one loop being of greater width and less height than its companion loop, tie wires having offset loops woven through the companion loops of said units, the legs of a tie wire loop extending between the inside of legs of a coil loop of greater width and the outside of legs of its companion coil loop of lesser width,

keeper ties of cord extending lengthwise of said row and rove through the eyes formed by the crowns of companion loops.

3. A spring comprising a plurality of coiled 5 spring units arranged in a row, contiguous spring units in a row having their terminal coils formed with diametrically opposite loops offset axially inward with relation to the units, one loop of a coil being of greater width than its other loop, 10 said coils being disposed with a loop of greater width and a loop of lesser width adjacent one another to form companions, tie wires having offset loops woven through the companion loops of said units, the legs of a tie wire loop extending 15 between the inside of legs of a coil loop of greater width and the outside of legs of its companion coil loop of lesser width, keeper ties of cord extending lengthwise of said row and woven

over the crown of one coil loop and under the crown of its companion loop.

4. A spring comprising a plurality of coiled spring units arranged in a row, contiguous spring units in a row having their terminal coils formed with loops offset axially with relation to the units, loops of adjacent coils being placed side by side to form companions, one loop being of greater width than its companion loop, tie wires having offset loops woven through the companion loops of said units, the legs of a tie wire loop extending between the inside of legs of a coil loop of greater width and the outside of legs of its companion coil loop of lesser width, keeper ties of cord extending lengthwise of said row and woven over the crown of one coil loop and under the crown of its companion loop. 80 85 90
